FACSIMILE APPARATUS

Charles J. Yeung, Ardmore, Pa., assignor to Radio Corporation of America, a corporation of Delaware

Application July 14, 1942, Serial No. 450,856

5 Claims. (Cl. 178—7.1)

1

This invention relates to facsimile apparatus and particularly to a transmitter form of device.

Generally speaking, this invention is directed to a form of facsimile apparatus in which provision is made for centering the optical scanning system relative to the record supporting surface, and at the same time positioning the record supporting surface fixedly relative to the scanning instrumentality.

Broadly speaking, the form of apparatus herein disclosed is related to the type of facsimile system set forth and described in my co-pending application Serial No. 440,923, filed April 29, 1942, now U. S. Patent No. 2,394,649, granted February 12, 1946, which discloses the general form of drive mechanism by which the scanning instrumentality is moved relative to the record holder to provide for the scanning of the subject of which the image is to be transmitted. Also, this invention is directed to the same general type of apparatus as that disclosed in my application filed concurrently herewith, which application relates primarily to the manner in which the record subject is held in fixed position relative to the record support surface.

In its preferred form, the apparatus for transmitting the pictures comprises a scanning instrumentality which rotates relative to a record support, and during the course of its rotation moves longitudinally of the record support, so that the subject carried by the record support is scanned to produce signal outputs representative thereof.

The apparatus for accomplishing this result consists essentially of a frame or support member upon which is mounted a movable scanning instrumentality which comprises a scanning head adapted to rotate relative to the record support, a drive motor and suitable gear box for rotating the scanning head relative to the record support and, at the same time, providing a suitable drive for moving the scanning head and complete drive assembly longitudinally of the record support for the purpose of scanning the record, and lastly, a photocell and amplifier combination which is energized in accordance with the light reflected through the scanning head so that the desired signal outputs are developed.

My co-pending application Serial No. 440,923, filed April 29, 1942, now U. S. Patent No. 2,394,649, granted February 12, 1946, discloses and claims the method by which the complete assembly of the motor, the gear box, the scanning head and the amplifier is rotated and moved relative to the record support surface.

The present application is concerned primarily

2

with the method and system for positioning the scanning elements relative to the record support, so that improved copies may be produced. In one of its forms, the present apparatus comprises a record support surface which is formed of a transparent plastic material such as that known in the art by the trade names of "Lucite" or "Crystalite." This record support is preferably formed as a half cylinder with the circumferential path thereof approximately equal to the length of one scanning line of the picture.

Because of the fact that plastics of this nature are somewhat of a non-rigid character unless properly supported, and because of the fact that the thickness of the material varies considerably under manufacturing tolerances, it is essential that the record supporting material be located very accurately relative to the optical system used for scanning. For this purpose, the supporting frame of the machine is formed so that each end is accurately machined to a circular formation, which is a true circle having a total circumference equal to two scanning lines. The plastic material which is to form the record support drum is to be braced against these rigid circular supports and securely clamped thereto from either end, so that the end portions are accurately shaped to a circular path and secured in such position, with the result that the plastic retains proper curvature throughout its length.

Next, the invention herein to be set forth is particularly concerned with suitable means for supporting the traveling optical system and its associated drive in such a manner that the optical system in its rotation shall be accurately aligned and positioned relative to the outer surface of the plastic record support upon which the record subject for transmission is to be carried. Also, in the disclosed apparatus, provision will be made whereby independent adjustments of such an optical system may be made at each end of the plastic support.

It accordingly becomes one of the objects of the present invention to provide ways and means for overcoming one or more of the defects of the prior art systems concerned with facsimile apparatus through the reduction of both size and weight of the equipment.

It also becomes one of the objects of the present invention to provide a suitable record support surface for carrying a subject of which the image is to be transmitted, which support surface shall not have the objections of prior art arrangements which use glass and which, because of the nature of the support, very frequently include bubbles or

striations which tend to reduce the quality of picture transmission.

Furthermore, it is an object of the present invention to provide a record support surface which shall avoid the objections of prior art arrangements using plate glass, which necessitated extremely careful bending of the glass and frequent breakage, or the very accurate grinding of a glass cylinder inside and out, which is almost prohibitive in such types of arrangements, due to excessive costs and the great danger of breakage which might, in some cases, necessitate complete interruption of the service of transmission.

A further object of the invention is to provide a convenient means for centering the optical system so that in its course of rotation, a light beam directed from the optical system through the transparent record support surface to the record and then back through the transparent record support surface to the scanning head optical system, and thence to the photocell, shall at all times be of equal length irrespective of the actual angular position of the scanning head relative to the support. It becomes essential that this optical path be retained of constant length because of the lenses necessarily used in connection with such apparatus, and, accordingly, a slight variance from a centermost position of the optical system relative to the record support and the supported record will vary to a very substantial extent the relative picture detail obtainable, because eccentricity of the optical system will produce a defocused scanning spot upon the record.

Another object is that of providing ways and means for mounting a plastic record support surface so that it may be easily replaced if scratched or worn, without making necessary a complete readjustment of the optical line-up and adjustment of the scanner.

Other objects and advantages of the present invention will of course become apparent and immediately suggest themselves to those skilled in the art to which the invention is directed from a reading of the following specification in connection with the accompanying drawing which shows, in perspective and partly in section, one of the suitable forms of such apparatus.

Referring now to the drawing, the supporting frame 11 comprises a circular upper section 13 and a rectangular lower section 15. The upper curved section 13 is divided into two separate end portions which are carried from the lower rectangular base support 15. The centermost part of the semi-circular upper support member or section 13 is notched at 17, and into these notched portions a cover section 19 (shown only in part) is adapted to rest. The cover section per se, and the manner of supporting the same relative to the complete assembly is set forth more particularly and claimed in my co-pending application filed concurrently herewith.

The ends of the upper semi-circular section 13 have, at their innermost portions, a ring-like section 21 which has its edge portion 23 very accurately machined to circular contour, and against this circular contour the transparent record support surface 25 is adapted to be placed and secured by means of ring members 27, as will hereinafter be more fully explained. These ring members, located at either end of the support, function as a sort of inside expansion clamp positioned within the ends of the supported member to hold it securely.

The rectangular base support members 15

carry, on one side, a channel section 29 which is adjustable in the direction shown by the arrows up and down, and which may be secured in any desired fixed position by means of suitable nuts clamping on the bolts 31.

Along one edge 33 of the channel 29 there is supported a grooved sliding member 35 which supports one side of a supporting housing 31 which is for the purpose of carrying and supporting the driving motor 39 for the complete assembly, the gear box 41 for rotating the scanning head 43 from the drive motor, and also for driving suitable gearing, later to be explained. Also, the support 37 is adapted to support and carry the amplifier and photocell combination, schematically shown at 45, all of which elements are arranged to slide and move longitudinally of the record support surface 25, in the direction shown by the arrows, and at the same time to move internally of the record support member 25.

The weight of the motor 39, the gear box 41, the scanning head 43 and the photocell and amplifier combination 45 and the associated gearing is also supported from slidable link support members 47 and 48 which are carried upon a shaft 49 which is, in turn, supported in the lower housing section 15. The lower end of the link support members 47 and 48 are formed as bearing surfaces 50 and 52, while the upper portion of these link members is adapted to support either end of the drive spindle 51. The link support members 47 and 48 are supported intermediate the bearing surfaces 50 and 52 through which the shaft 49 passes and the upper portion which supports the spindle 51, so that these links are rigid with respect to the supporting frame for the scanning head assembly.

As was explained in my co-pending application Serial No. 440,923, filed April 29, 1942, now U. S. Patent No. 2,394,649, granted February 12, 1946, a spindle 53 is adapted to be held in the frame support sections 15, and, by motion of the lever arm 55 (only partially shown since it is shown in my co-pending application Serial No. 440,923, filed April 29, 1942), now U. S. Patent No. 2,394,649, granted February 12, 1946, the spindle 53 is adapted to be rotated to a slight extent in the direction shown by the arrows adjacent it, so as to bring the movable half nut 57 into and out of engagement with the threads 58 on the drive spindle 51. As is evident from the drawing, engagement of the half nut 57 with the threads 58 on the drive spindle 51 will tend to cause the link support members 47 and 48 to move longitudinally of the support shaft 49 and to move the complete supported assembly in the same direction, so that sliding contact is also maintained by the slotted member 35 being supported by the edge 33 of the L-shaped member 29.

For the purpose of rotating the drive spindle 51, the motor 39 is energized (from a source not shown), and, through suitable gearing (not shown) causes the scanning head 43 to rotate about the shaft 61 as an axis. Similarly driven from the same motor source, the shaft or spindle 63 carrying the worm 65 is adapted to turn the pinion 67 which is keyed to the drive spindle 51. The result is that when the half nut 57 is made to engage the threads 58 of the drive spindle 51, the rotating motor causes the complete assembly of the motor, the gear box, the scanning head and the photocell and amplifier combination to move internally of the support 25. This arrangement, it is thus evident, is one in which the lead

screw 51 is supported on the traveling member and thus facilitates the drive from the motor 39 which is carried on the sliding carriage, and it also facilitates the engagement and disengagement of the half nut 57 which is carried upon the frame member proper.

The scanning head, it will be seen, comprises a plurality of conically shaped members 69 and 69' with a suitable optical system 71 arranged to direct light from a source (not shown) within the scanning head outwardly toward the support surface 25, and then backward through the scanning head and, by appropriately chosen means, into the photocell and amplifier combination, all as explained in my co-pending application Serial No. 440,923, filed April 29, 1942, now U. S. Patent No. 2,394,649, granted February 12, 1946.

When the light passing out of the optical system 71 to the subject for transmission which is supported upon the transparent support 25 is reflected, it is reflected internally of the conical member 69 and thence, by a reflecting member not shown, but shown in application Serial No. 440,923, filed April 29, 1942, now U. S. Patent No. 2,394,649, granted February 12, 1946, it is arranged to vary the photo emission of a photocell contained within the photocell and amplifier combination 45. Thus there is produced a variance of output from the amplifier which is proportional to the intensity of light and shadow on the record surface. If, however, the optical system is not accurately positioned relative to the record support member 25 and if it is not so aligned that the length of optical path from the light source to the subject and thence back to the photoelectric cell is always identical, the effects of defocusing will be apparent and adequate sharpness will not be present in the transmitted and received pictures or facsimiles.

Accordingly, to provide adjustment of the scanning head so that it shall be properly centered relative to the record support 25, the end bearing members 73 and 75 for the shaft 49 are formed as eccentrics 77 and 79, and the eccentricity may be varied by means of rotation of the bearing surfaces 77 and 79 relative to the main bearing members 73 and 75 by means of a slot-like member 81 for the eccentric bearing 77 which is capable of being turned. A similar member is provided for the eccentric bearing 79 but is not shown in the drawing.

When the bearing surface 77 is rotated, it is apparent that the shaft 49 and the link members are moved transversely in accordance with the variance in eccentricity of the variant, and because the link members are formed as a rigid part of the housing support for the drive means, the scanning head and the photocell and amplifier combination it is apparent that the entire assembly may be laterally shifted by the rotation of the eccentrics.

In order to provide so that the optical path shall always be of equal length, the assembly, when first set up, is so arranged that the scanning head member is turned relative to the semi-circular support ring, and particularly the accurately machined edge 23 thereof, so that the cone member 69, for instance, comes opposite a point generally designated as A on the accurately machined member, and the spacial separation between the optical system 71 and this point A is then measured. It is, of course, appreciated that under such circumstances the transparent support surface 25 has not yet been positioned, and the clamping ring 27 is of course also miss-

ing. Then the scanning head 43 is rotated through 180° and the spacial separation between the optical system 71 and a point on the ring member 23 diametrically opposite the point A is carefully measured as to its spacing from the said optical system. Generally speaking, this last named point would correspond closely to that point designated as B on the drawing, although it is to be understood that because of the portion of the drawing broken away, the actual point B which is used for alignment cannot be shown. If there is a difference in the spacing of the optical system under such conditions from points A and B, then the eccentrics are adjusted until equal distance spacing is provided, or, in other words, the distance from the center of rotation to each of points A and a diametrically opposite point (considered as B for illustrative purposes) is equal. Under such circumstances, it can be appreciated that the spacing from the center of the shaft 61 to the machined edge 23 at points A and B represents the true desired radius which must be obtained for all angles of rotation.

However, it is next necessary to adjust the length of the optical path at intermediate locations, and, accordingly, at a point such as that shown by point P for instance, a measurement is again taken and the eccentric 77 is adjusted in position so that there shall be the same spacial separation between the optical element 71 and the point P as there was between the optical element and points A or B when the scanning head was in horizontal position. The point P is chosen as corresponding to that formed by a line assumed to be drawn between the center of the shaft 49 and the center of the shaft 61 upon which the optical system rotates as its axis. This makes the distance between the center of rotation 61 and point P equal to that previously found for the distance between point 61 and either A or B, but it would result in making the distances between point 61 and A and B no longer equal.

Next, the optical system of the scanning head is turned throughout a 90° angle to the point P (to a point which angularly will approximately correspond to point Q) and a measurement, representing the distance between the optical element 71 and the accurately machined circular surface 23 is there taken. If this measurement fails to correspond to the spacial separation between the end of the optical system 71 and the point P, it is apparent that an adjustment must now be made in this new direction. This last named adjustment is accomplished by moving the channel section 29 on which the support 37 is adapted to slide by virtue of the supported sliding member 35 up or down in the directions shown by the arrows by loosening the nuts on the bolts 31; and, this adjustment is made until the spacial separation between the optical elements 71 and the point 90° removed from the point P shall be equal to the spacial separation between the optical system 71 and the point P.

After the measurements above stated have been made at one end of the support, the complete scanning head assembly is moved to the opposite end of the support, so that the scanning head would be arranged to scan a supported subject at the right hand edge of the record support 25 (assuming it were in position), and adjustments and measurements corresponding exactly to those above explained are repeated by adjusting, for instance, the eccentric 79 and then the positioning of the right hand end of the channel section. Then the adjustment is checked at the

first end, and, when accurately established, it will be found that further adjustment is unnecessary.

Now, to position the record support surface 25 with regard to the remainder of the support, this element is placed in position, as indicated by the drawing, until one edge 83 thereof comes between the vertical edge of the clamp member 85 and the edges 100 of the frame support, and of course the outer surface of the record support 25 is caused, at its ends, to bear up against the accurately machined semi-circular portion 23 of the main support.

It was above explained that the support member 25 is preferably of a plastic type and since plastics, as a general class, are usually subject to cold flow, as well as thermal distortion, the support means herein described is for the purpose of correctly shaping the plastic material when it is installed and then for maintaining such shaping.

Next, the outer edge or face of the plastic member 25 is caused to press up against the machined semi-circular section 23 and the ring member 27 is secured by the clinch plate 87, which has an L-shaped outer support capable of holding both the ring member 27 and the support 25, and when these members are tightly pressed against the machined semi-circular edge 23, the support will be properly positioned. A clinch plate 87, also not shown, is positioned diametrically opposite that one already indicated. From the above, it will be appreciated that these plates exert no circumferential force on the support 25 but serve to hold the edges thereof in an outward direction against the edges 100 of the frame member 15, which edges 100 have been made straight and true and flush at their ends with the surfaces 23.

At the opposite end of the support frame a similar ring member 27 is positioned to hold the opposite end of the record support 25. It thus becomes obvious that with the scanning head assembly having already been adjusted in its position relative to the carefully machined semi-circular edge 23 and the record support surface 25 rigidly positioned relative to this same surface, the length of the optical path remains invariant when a record subject 89 is positioned thereupon.

As is apparent from the drawing, the plastic member 25 need not seat itself at the bottom of the clinch plate 87, nor yet need it press directly against the upper surface of the clamp 85, but rather it must merely be held between the edge 100 of the frame and the upright section of the clamp 85. This then provides for the possibility of the plastic member expanding with temperature changes and permits it to move slightly along a circular path relative to its support. It is apparent, of course, that the coefficient of expansion of the plastic is greater than that of the metal, and therefore some provision is made for permitting the length of the plastic to change without changing in any way its support or mounting position.

In further consideration of this invention, it has been pointed out above that the plastic member 25 is of substantially semi-cylindrical shape, but it is to be understood, of course, that the plastic support need not necessarily be of the semi-cylindrical configuration. If, however, the arc subtended by the plastic material be other than the substantially 180° arc subtended by the arrangement illustrated by the drawing, then it is apparent that the number of scanning

heads must be changed. If, for instance, the plastic member were to extend only for 120°, then three separate scanning heads would be provided for the scanning device with the spacings thereof being substantially 120°. In any case, the plastic member is formed as a surface of revolution and it is so positioned that the outside of the transparent or plastic material is adjacent to a machined edge and so referenced that when the adjustment of the axis of rotation of the scanning head is made, the length of the optical path shall remain substantially invariant.

Other and further modifications of the invention of course may readily be made, provided the changes fall fairly within the spirit and scope of what has herein been set forth.

What I claim is:

1. Facsimile apparatus comprising a partially cylindrical transparent record support member, a movable and slidable member, a rotary scanning device, a drive unit for rotating said scanning device, and an amplifier unit for the said scanning device all carried upon the said slidable member and all positioned internally of the said record support member, means including guide elements for the slidable and movable member for causing the rotary scanning element, its drive element and the associated amplifier all to move longitudinally of and internally of the said partially-cylindrical support member, means for adjusting the center of rotation of the scanning element in each of two directions normal to the direction of longitudinal motion so as to locate the scanner in predetermined positions relative to the partially-cylindrical support member so that the said rotary scanner rotates upon an axis approximately corresponding to the center of the curvature of said partially-cylindrical support member.

2. Facsimile apparatus comprising a substantially semi-cylindrical transparent record support member, a rotary scanning device and associated drive positioned internally of the said support member with the scanning device being adapted to rotate upon an axis approximately corresponding to the center of curvature of the semi-cylindrical support member, means including guide elements for causing the rotary scanning element and its drive to move longitudinally of and internally of the said semi-cylindrical support member, means for adjusting the center of rotation of the scanning element relative to the semi-cylindrical support member, said adjusting means comprising a laterally adjustable means for shifting the said rotary scanning means and its associated drive in a direction which is normal to the direction of motion of the said scanning means during scanning relative to the semi-cylindrical support member, means for moving one of the said guide elements in a direction which is normal to the direction of motion of the scanning device and its associated drive and also normal to the path of the first said adjustment, whereby rotation of the scanning device is caused to take place about an axis providing equal radial distances between the scanning device and all points on the semi-cylindrical record support element.

3. Facsimile apparatus comprising a transparent record support member formed as a surface of revolution, a rotary scanning device and associated drive positioned internally of the said support member with the scanning device being adapted to rotate about an axis approximately corresponding to that of the surface of revolution, said scanning device including a plurality of scanning heads with the number thereof being

directly related to the angle subtended by the arc of said surface, means including guide elements for causing the rotary scanning heads and the drive element therefor to move longitudinally of and internally of the said transparent record support member, means for adjusting the center of rotation of the scanning devices relative to the transparent record support member, said adjusting means comprising means for shifting the said rotary scanning means and its associated drive in two directions each normal to each other and each normal to the direction of motion of the scanning head and its drive relative to the transparent record support member.

4. Facsimile apparatus comprising a transparent record support member formed as a surface of revolution and being of substantially equal radius at all points on the surface, a rotary scanning device and associated drive positioned internally of the said support member with the scanning device being adapted to rotate about an axis approximately corresponding to that of the surface of revolution, said scanning device including a plurality of scanning heads of a number equal to 360° divided by the angle subtended by the arc of the transparent support surface, a light source positioned substantially upon the axis of rotation of the scanning device, optical means to direct the light from the source through the scanning heads to the record support member, means including guide elements for causing the rotary scanning device and its drive to move longitudinally of the said transparent support member, means for adjusting the center of rotation of the scanning device relative to the said transparent support member, said adjusting means comprising means for shifting the said rotary scanning device and its associated drive in two directions each perpendicular to each other and each perpendicular to the direction of motion of the said transparent record support member.

40

tion of the scanning device relative to the transparent support member so that the length of the light path from the source to the transparent support remains substantially constant for all angles of rotation of the said scanning device.

5. A facsimile device comprising a rotary scanning element, drive means for rotating said scanning element, and means for moving the scanning element and the rotating drive means therefor along a predetermined limited length longitudinal path during rotation of the scanning element, a frame support for the scanning element and the drive means therefor positioned externally of and so as substantially to surround the said scanning element, said frame support having a partially-cylindrical configuration at each of two extreme positions of longitudinal movement of the scanning element, means for positioning a substantially transparent and elongated record supporting element in such manner as to cause said record element to conform throughout its length substantially to the partially-cylindrical configuration of the frame support, said elongated transparent record support element having substantially the same length as the path of longitudinal motion of the scanning element, means for clamping the curved edges of the supported transparent element rigidly against the partially-cylindrical surface of the frame support element so that the curved configuration is established throughout the length of the said element, means for clamping substantially the complete linear edges of the supported transparent member to the frame member and means for adjusting the scanning element and its drive on the supporting frame element so as to maintain uniform positioning in all rotational positions between the scanning element and the record supporting element.

CHARLES J. YOUNG.
